MUSICAL TOY GUN

Morris Gurtov, New York, N. Y.

Application March 5, 1954, Serial No. 29,384

Term of patent 7 years

(Cl. D34—15)

To all whom it may concern:

Be it known that I, Morris Gurtov, have invented a new, original, and ornamental Design for a Musical Toy Gun, of which the following is a specification, reference being had to the accompanying drawing, forming a part hereof, in which,

Fig. 1 is a perspective view of a musical toy gun showing my new design;

Fig. 2 is a top plan view; and

Fig. 3 is an end view thereof.

In the drawing the side of the musical toy gun which does not appear has substantially the same appearance as the side shown in Fig. 1.

I claim:

The ornamental design for a musical toy gun, substantially as shown and described.
